(57) **CLAIM**

I claim the ornamental design for a ribbon-shaped handle for a container, as shown and described.

DESCRIPTION

FIG. 1 is a front perspective view of a ribbon-shaped handle for a container;

FIG. 2 is a side elevation view thereof;

FIG. 3 is a top plan view thereof; and,

FIG. 4 is a bottom plan view thereof.

The dashed lines are for illustrative purposes only and form no part of the claimed design.
